UNITED STATES PATENT OFFICE.

JOHN OSCAR THIEL, OF NEWBURG, MISSOURI.

REGULATOR FOR FEED-WATER HEATERS.

1,146,669.

Specification of Letters Patent. Patented July 13, 1915.

Application filed July 3, 1914. Serial No. 343,760.

To all whom it may concern:

Be it known that I, JOHN O. THIEL, a citizen of the United States, and a resident of Newburg, in the county of Phelps and 5 State of Missouri, have invented a new and Improved Regulator for Feed-Water Heaters, of which the following is a full, clear, and exact description.

My invention relates to regulators or controllers for feed-water heaters, and has reference more particularly to a device which will automatically cut off the supply of the feed-water heating medium when the temperature of the water has risen above a predetermined one, or which will automatically feed into the water the said medium when the temperature of the water has fallen below a predetermined point. The device is also adapted to regulate the temperature of 10 the feed-water relatively to the surrounding temperature.

An object of the invention is to provide a simple, efficient and convenient controller for feed-water heaters which is automatic in 15 its action and which is so arranged that any mishap will place the feed-water heater into the safety position.

With the above and other objects in view, the nature of which will more fully appear 20 as the description proceeds, the invention consists in the novel construction, combination and arrangement of parts as herein fully described, illustrated and claimed.

In the accompanying drawings, forming 25 part of the application, similar characters of reference indicate corresponding parts in all the views, and Figure 1 is an embodiment of my invention as applied to a locomotive; Fig. 2 is an enlarged elevated view of the 30 regulator; Fig. 3 is a similar view showing the regulator in a different position, that is, the supply of the heating medium is cut off by the controller; and Fig. 4 is a detail view of the valve for adjusting the machine.

Referring to the drawings, 5 represents a water tank provided at the bottom thereof with a shallow chamber 6 extending substantially over the entire bottom of the tank. The chamber 6 has an inlet 7 connected to

the exhaust pipe 8 of the pump 9 by a two-way valve 10, the crank 11 of which is connected to a piston rod 12 of an air cylinder 13 by a connecting rod 14.

The valve 10 is maintained in inoperative position by a coil spring 15 mounted on the piston rod 12 within the cylinder 13, as indicated in Fig. 3. The piston 16 within the cylinder is moved by compressed air flowing from a suitable source through a conduit 17 and for which two valves 18 and 19 are provided. Between said valves a bracket 20 is mounted forming a support for a centrally pivoted arm 21 the ends of which engage the valves 18 and 19. The arm 21 has a central extension 22 engaging a socket 23 of a member 24 which is pivotally connected to a lever 25. The lever is, in turn, pivotally connected to a standard 26 carried by a float 27, the float 27 being mounted in a tank 28 which is in communication with a closed tank 29 and 30 which tank 29 forms an air chamber to be influenced by the surrounding atmosphere. The expansion or contraction of the air within the chamber of the tank 29 will vary the position of the float within the tank 28 and, therefore, the position of the lever 25. It will be noted that when the float 27 moves the lever 25 moves therewith on the pivot connecting the lever 25 to the member 24.

Positioned within the tank 5 is an air 35 chamber 30 which is connected to an air-tight receptacle 31 by a conduit 32. The air-tight receptacle 31 is preferably cone-shaped, and within this receptacle 31 below 40 the bellows 33 are provided, the lower edge of the bellows 33 being clamped to the bottom of the receptacle 31, while the upper edge, which is free to move, is provided with a rigid member 34 from which a rod 35 extends through the bottom of the receptacle 31. 45 The projecting end of said rod 35 engages the end of the lever 25 extending from the member 24.

When the temperature of the water within the chamber 5 falls below a predetermined point, the air within the chamber 30 contracts and the air within the bellows 33 expands, raising the member 34 and there-

with the rod 35. This initial movement of the rod 35 permits the spring 36 provided on the valve 19 to move the arm 21 on its pivot and thus move the lever 25 on its pivotal connection with the standard 26. To reduce the resistance to the spring 36 the lever 25 is provided with a counterweight 37. This movement of the lever 21 actuates the valve 18 and the action cuts off the connection of the conduit 17 from the atmosphere and establishes communication between the conduit 17 and the conduit 38 which leads to a suitable supply of compressed air. The action of the spring 36 also opens the valve 19 (see Fig. 2). The compressed air entering the cylinder 13 will move the piston 16, causing the movement of the valve 10; thus, the exhaust steam from the pump 9 will be switched from the smoke stack to the chamber 6 in the water tank 5. The passage of the exhaust steam through the chamber 6 will raise the temperature of the water and the air in the air chamber 30 will expand, causing the bellows 33 to collapse, thus forcing the rod 35 out of the receptacle 31. The end of the rod 35 coming in engagement with the end of the lever 25 will operate the same and cut off the supply of exhaust steam. The distance between the end of the rod 35 and the end of the lever 25 depends on the position of the float 27 within the tank 28; and since the position of said float 27 depends on the expansion of the air in the tank 35 which is under the influence of the surrounding atmosphere, a proper adjustment of the device is obtained whereby the temperature of the water within the tank 5 is controlled relatively to the atmosphere. The conduit 32 is provided with a valve 39, the object of which is to adjust the machine. It will be seen from the drawings that if any leak of air should occur in any part of the device formed by the air tank, air receptacle 31, conduit 32 and the bellows 33, the rod 35 will move to the operative position and place the device into safety position, that is, cut off the supply of exhaust steam to the chamber 6. It is evident that the valves 18 and 19, receptacles 28, 29 and 30, and the system of leverage associated therewith, can be positioned in any other part than that shown in Fig. 1, as, for example, on the tank 5. From the foregoing description, taken in connection with the accompanying drawings, the advantage of the construction and operation of the device shown will be readily understood by those skilled in the art to which the invention pertains; and while I have described the principle of operation, together with the device which I now consider to be the best embodiment thereof, I

desire to have it understood that the device shown is merely illustrative and that such changes may be made when desired as are within the scope of the appended claims.

Having thus described my invention, I claim as new and desire to secure by Letters Patent:

1. In a device of the class described, a water tank, means for supplying heat to the tank whereby the water is heated, compressed air operable means for turning the heat on or off from the water in the tank, bellows inclosed in the air chamber, part of the said chamber being associated with the water in the tank whereby by a change of temperature of the water said bellows are adapted to be actuated; a system of levers connecting said bellows with said compressed air operable means and through the medium of which said bellows are adapted to place said means in operative or in inoperative position, and means associated with the system of levers adapted to be influenced by the atmospheric temperature whereby the action of said bellows on said compressed air operable means may be accelerated or retarded.

2. In a device of the class described, a water tank, an air chamber in the tank, a steam supply associated with the tank for heating the water therein, compressed-air-operable means controlling the supply of steam to the tank, a second air chamber associated with the air chamber in the tank, bellows in said chamber, means associated with the bellows and adapted to move therewith, a system of levers from said last-mentioned means to the compressed-air-operable means whereby said bellows are adapted to place said compressed-air-operable means in operative or in inoperative position, a liquid tank, a float therein associated with the system of levers, and an air chamber associated with the said second tank for varying the position of said float whereby the action of said bellows on said compressed-air-operable means can be accelerated or retarded.

3. In a device of the class described, a water tank, a steam supply for heating the water in the tank, compressed air operable means for turning the steam on and off from the water, bellows operable by the contraction or expansion of the air caused by the variation of temperature of the water in the tank, and means operable by the atmospheric temperature variation including a system of levers positioned between the said bellows and said compressed air operable means, substantially as and for the purpose set forth.

4. In a device of the class described, a water tank, a medium for heating the water

in the tank, compressed air operable means controlling the supply of the medium to the tank, valves for controlling the supply of compressed air to the compressed-air operable means, means for operating the valves controlled by the temperature variation of the water in the tank, and means operable by the atmospheric temperature variation positioned between the valves and

the means for operating the valves, substantially as and for the purpose set forth.

In testimony whereof I have signed my name to this specification in the presence of two subscribing witnesses.

JOHN OSCAR THIEL.
